BRADLEY DEWEY, OF CAMBRIDGE, MASSACHUSETTS, AND THEODORE T. MILLER, OF ORANGE, NEW JERSEY, ASSIGNEES TO DEWEY & ALMY CHEMICAL COMPANY, OF CAMBRIDGE, MASSACHUSETTS, A CORPORATION OF MASSACHUSETTS.

METHOD OF CONDITIONING CAN COVERS FOR SEALING.

Application filed February 17, 1925. Serial No. 9,823.

To all whom it may concern:

Be it known that we, BRADLEY DEWEY and THEODORE T. MILLER, both citizens of the United States of America, and residents 5 of Cambridge and Orange, in the counties of Middlesex and Essex and States of Massachusetts and New Jersey, respectively, have invented new and useful Improvements in Methods of Conditioning Can Covers for 10 Sealing, of which the following is a specification.

In the case of the sanitary or open top metal cans one of the most common methods of making them air-tight is by double 15 seaming the can cover and body. This operation is ordinarily accomplished by spinning the peripheral edge of the can cover and a comparatively small flange formed on the can body into a double seam. However, 20 before the double seaming operation is performed lining material is deposited over the sealing area of the cover so that after the operation this lining material cooperates with the double seam for effecting an air-tight joint thus preventing the contents of 25 the can from spoiling or deteriorating.

Heretofore in practice it has been customary first to crimp or curl the peripheral edge of the can covers, apply the lining material 30 under the curled flange, and thereafter dry the lining material to form a gasket. While this practice is possible with rubber latex compounds such as are described in the co-pending application of Bradley Dewey and 35 Ernest C. Crocker, Serial No. 719,129, filed June 10, 1924, nevertheless it is greatly complicated by the excessive time necessary to dry the water base of such emulsions. Furthermore the drying period of this water is 40 retarded by the formation of a film of rubber over the surface of the compound at the edge of the curl. This film entraps the water in the compound under the curl and as a result if additional heat is applied in 45 order to hasten the evaporation of the water there results sufficient steam to form a blister in the film. This blister then breaks with volcanic effect and in breaking spatters compound and results in an unsightly appearance,

Objects of this invention are therefore to overcome the above difficulties and to produce a method for conditioning can covers for sealing having the novel arrangement of steps hereinafter described.

The invention consists of a novel method for conditioning can covers for sealing which generally comprises the following succession of steps; first depositing liquid lining material on the covers before said 55 covers have been completely curled, drying the material on the cover, and finally crimping the peripheral edge of the cover preparatory to the sealing operation. If desired, between the depositing and drying steps the 60 lining material may be uniformly spread over the sealing area. An outstanding feature of the above method is that the lining material on the covers is dried (either completely or in substantial degree) before the 65 peripheral edges thereof are curled. During the drying operation therefore, the lining material is not pocketed or trapped under curled edges and the exposed area of the material is more extensive (relative to 70 the volume of the material) whereby the material may be more rapidly dried at higher temperatures without blistering or 75 spattering.

For purposes of illustrating the invention 80 an apparatus is shown on the accompanying drawings in which:

Fig. 1 is a side elevation of an apparatus for applying lining material to covers, together with an apparatus for redistributing 85 the material over the covers, and a part of an apparatus for drying the material on the covers;

Fig. 2 is a section on the line 2-2 of 90 Fig. 1;

Fig. 3 is a section on the line 3-3 of Fig. 1;

Fig. 4 is a side elevation of an apparatus for drying the lining material on the covers;

Fig. 5 is an end elevation of the apparatus 95 shown in Fig. 4;

Fig. 6 is a section on the line 6-6 of Fig. 4;

Fig. 7 is a top plan view on a reduced 100 scale of a drying apparatus;

Fig. 8 is a top plan view of an apparatus for curling the peripheral edges of the cover;

Fig. 9 is a plan view of a cover;

5 Fig. 10 is a section on the line 10—10 of Fig. 9; and

Fig. 11 is a view similar to Fig. 10 showing the edge of the cover curled.

The can covers X are in the form of annular disks provided with a peripheral flange Y and an annular shoulder Y' defining therebetween an annular groove Z into which the lining material is scraped. The liquid lining material or sealing compound 15 for the covers is preferably in the form of a viscous and plastic liquid.

An illustrative embodiment of the invention comprises an apparatus A for applying equal quantities of liquid lining material to 20 each can cover X and for distributing the material circumferentially of the cover. After the lining material has been distributed circumferentially over the covers, they are then conducted past a redistributor B 25 which redistributes or spreads the material evenly over the sealing area. Although the lining material is spread evenly over the covers X in the form for sealing it is still in a liquid state and before curling the peripheral flange Y preparatory to applying the 30 covers to the cans it is desirable to dry the material thus eliminating liability of displacement of the liquid from the sealing area. For this purpose, the covers are conducted to a heated drier C where they are 35 continuously rotated for a predetermined length of time until the sealing material is thoroughly dry, and then the peripheral flange on the covers is turned or curled by an 40 apparatus D preparatory to applying the covers to the cans.

Referring more particularly to the drawings the apparatus A for applying the lining material to the covers comprises a flat support 1 having legs 2 upon which rests an 45 elongate rectangular pan 3 containing the liquid lining material. An applying roll 4 is supported in the brackets 5 on the support 1 and dips into the bath of the lining material which adheres to the roll, thereby 50 forming a coating over its entire length. In order to maintain the coating uniform in thickness, a scraper roll 6 is spaced therefrom a slight distance (for example, approximately 55 thirteen-thousandths of an inch.) It will be observed that the scraper roll 6 is smaller than the applying roll and is supported above the bath of sealing liquid.

The rolls are rotated in the same direction, 60 preferably the scraping roll being driven considerably slower than the applying roll and the latter dipping into the bath and bringing up a relatively thick coat of the liquid while the scraper roll smoothes the 65 liquid coat on the applying roll and prevents

the accumulation of an excess amount thereon, which would form a streaked and uneven coating. For driving the rolls, a pulley 7 is fixed to one end of the applying roll 4 and a pulley 8 larger than the pulley 7 is 70 fixed to the scraper roll 6 at the end opposite from the pulley 7. A driving shaft 9 mounted on suitable brackets beneath the legs 2 is connected to rotate the pulleys 7 and 8 by belts 10 and 11 respectively which 75 pass around pulleys fixed to the shaft, and the driving shaft may be driven from any suitable source of power applied to the pulley 12.

The can covers X are rolled along the applying roll on the face opposite from the scraper roll at a sufficient angle for the lining material to flow or be scraped on the covers in the annular groove Z and for this purpose an endless cable 13 of rubber passes around a sheave 14 which is fixed to a shaft 14' mounted on one end of the support 1 and extends substantially parallel with the face of the applying roll 4 over guide sheaves 15 and over a sheave 16 mounted on an arm 17 secured to the drier C. A weighted sheave 18 on the cable 14 holds the cable taut and in order to drive the cable 13 a sheave 19 fixed to the shaft 14' is connected by a belt 20 which encircles a sheave fixed to the driving shaft 9. Thus by rotating the shaft 9 both the applying roll 4 and scraper roll 6, together with the endless cable 13 are driven. The lower edges of the covers X are supported on a guide 21 which extends parallel to the applying roll 4 and is mounted in close juxtaposition thereto.

In order to insure uniform distribution of the sealing material circumferentially of the cover X and proper spreading transversely of the groove Z in the cover, an elongate nozzle 22 is provided with a slot extending substantially its entire length through which air may be forced. The covers X are conducted from the guide 21 to a guide 23 by 105 the cable 13 so that the upper part of the groove Z lies beneath the slot in the nozzle 22. The arrangement is such that the air blowing through the nozzle is split by the peripheral flange of the cover, and as the cover is rolled along the air impinges against the sealing liquid and spreads it over the groove Z and a part or the whole of the peripheral flange Y, as indicated in Fig. 10.

For the purpose of drying the sealing liquid on the covers a drier C is provided adjacent the redistributor B and the covers X with the lining material applied thereto and distributed in the form for sealing are conducted into the drier from the guide 23 whereupon they are continuously rotated and carried along for a predetermined period until the sealing material is thoroughly dry.

The drier C comprises a metal casing hav-

ing side walls 24, bottom 25, and rounded end walls 26, and a lining 27 of asbestos board or the like is spaced from the inner walls thereof, the space between the casing and housing being filled with an insulating filler 29 so that the interior of the drier is thoroughly insulated from the surrounding atmosphere. The drier is provided with a detachable cover 28 to afford access to its interior. Supports 30 are mounted adjacent opposite ends of the metal casing for holding the drier in substantially a horizontal position. Extending horizontally within the housing adjacent the bottom thereof is a heater 31 in the form of an elongate nozzle having a plurality of openings through which fuel such as combustible gas may be passed thereby heating the interior.

The covers X are introduced into the drier C through an opening 32 at one side near the bottom thereof and an endless cable 33 is provided for rolling the covers around the inside of the housing 27 progressively upward until finally discharged at the top. The length of time required to carry the covers through the housing is predetermined so that when discharged the lining material has dried. The cable 33 passes around alternately one of the sheaves 34 at one end of the housing and one of the sheaves 35 at the other end of the housing, the sheaves being mounted in staggered relation and the cable passing through an opening 36 adjacent the top of the drier for discharging the covers. The sheaves 34 and 35 are mounted upon vertical shafts 37 suitably supported at opposite ends of the casing and in order to guide the covers X a spiral track 38 of angle iron is provided along the path of the cable 33 although disposed below and at one side thereof so that the edge of the covers rests on the track as they are rolled along, as indicated in Fig. 6.

From the discharge opening 36 the cable 33 passes around a sheave 39, thence over a sheave 40, thence over a sheave 41 having the weight 42 to maintain the cable taut, and thence around a sheave 43 from which it extends into the drier through the opening 32. The sheaves 40 and 43 are mounted on a common shaft 43' supported on the uprights 44 which also serve to support the sheave 39, and in order to drive the cable 33, a drive pulley 45 which may be connected to a suitable source of power is mounted on a shaft 46 to which is fixed a gear 47, meshing with a gear 48 on the shaft 43'. The usual idler pulley 49 may be provided adjacent the drive pulley 45 if desired.

Before performing the double seaming operation hereinbefore mentioned in order to secure the covers X to the can bodies, the upstanding peripheral flanges Y are curled over and an apparatus D for performing

this operation (Fig. 8) comprises a circular disc having a bevelled periphery 50 suitably mounted and driven from the pulley 51. The covers X are fed to the periphery of the disc 50 over a slide 52 and the disc 50 which is rotated at a relatively high rate of speed forces the covers around the circular guide 53 into a discharge guide 54. The bevelled periphery of the spinning disc 50 engages the peripheray flange Y of the covers and curls it over as shown in Fig. 11 so that the covers are now ready to be applied to the can body. This curling operation does not displace the lining material because the latter is thoroughly dry and adheres to the metal of the cover.

Without further analysis, the foregoing will so fully reveal the gist of this invention that others can by applying current knowledge readily adapt it for various applications without omitting certain features that from the standpoint of the prior art, fairly constitute essential characteristics of the generic or specific aspects of this invention, and therefore such adaptations should and are intended to be comprehended within the meaning and range of equivalency of the following claims.

We claim:

1. The method of conditioning a can cover for sealing which consists in successively applying liquid lining material to the cover in the form for sealing, drying the material on the covers, and thereafter curling the peripheral edge of the cover preparatory to sealing.

2. The method of conditioning a can cover for sealing which consists in successively propelling the can cover along a predetermined path, depositing liquid lining material on the cover in the form for sealing, drying the lining material on the cover, and thereafter curling the peripheral edge of the cover preparatory to sealing.

3. The method of conditioning a can cover for sealing which consists in successively depositing liquid lining material on the cover in the form for sealing, distributing the material over the cover in a uniform manner, drying the material on the cover, and thereafter curling the peripheral edge preparatory to sealing.

4. The method of conditioning a can cover for sealing in which the cover is successively conveyed from one step to the next, said steps consisting in applying liquid lining material to the cover, drying the material on the cover, and finally curling the peripheral edge of the cover.

5. The method of conditioning a can cover for sealing in which the cover is successively conveyed from one step to the next, said steps consisting in applying liquid lining material to the cover, redistributing the material on the cover in the form for seal-

ing, drying the material on the cover, and finally curling the peripheral edge of the cover.

6. The method of conditioning a can cover
5 for sealing which consists in continuously moving the cover in a predetermined path and during its movement successively applying liquid lining material, redistributing

said material in the form for sealing, drying the material, and curling the peripheral 10 edge thereof.

Signed by us at Cambridge, Mass. this 11th day of February 1925.
